UNITED STATES PATENT OFFICE

137,256

DESIGN FOR AN EMBROIDERED TEXTILE FABRIC

Adolph Lehmann, New York, N. Y.

Application January 6, 1944, Serial No. 112,177

Term of patent 3½ years

To all whom it may concern:

Be it known that I, Adolph Lehmann, a citizen of the United States, residing in New York city, in the county of New York and State of New York, have invented a new, original, and ornamental Design for an Embroidered Textile Fabric, of which the following is a specification, reference being had to the accompanying drawing, forming part thereof.

The figure is a plan view of an embroidered textile fabric, embroidered in contrasting colors or in varied shades. The colors or shades are indicated on the drawing by shadings of three

different intensities, light, medium, and heavy. The dot and dash lines A—A and C—C on the drawing outline a unit which repeats the color combination in regular succession as indicated by the extensions beyond the unit boundary. The dot and dash lines A—A and B—B on the drawing outline a design unit which repeats three times within the color repeat A—A to C—C.

I claim:

The ornamental design for an embroidered textile fabric, substantially as shown and described.

ADOLPH LEHMANN.
